(57) **CLAIM**

The ornamental design for a collapsible target, as shown and described.

DESCRIPTION

FIG. 1 is perspective view of a collapsible target embodying my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the collapsible target of FIG. 1 shown in a stacked configuration of two such collapsible targets;

FIG. 9 is a front view of the collapsible targets of FIG. 8;

FIG. 10 is rear view of the collapsible targets of FIG. 8;

FIG. 11 is a left side view of the collapsible targets of FIG. 8;

FIG. 12 is a right side view of the collapsible targets of FIG. 8;

FIG. 13 is a top view of the collapsible targets of FIG. 8;

FIG. 14 is a bottom view of the collapsible targets of FIG. 8;

FIG. 15 is a perspective view of an alternate embodiment of the collapsible target of FIG. 1;

FIG. 16 is a front view of the collapsible target of FIG. 15;

FIG. 17 is rear view of the collapsible target of FIG. 15;

FIG. 18 is a left side view of the collapsible target of FIG. 15;

FIG. 19 is a right side view of the collapsible target of FIG. 15;

FIG. 20 is a top view of the collapsible target of FIG. 15; and,

FIG. 21 is a bottom view of the collapsible target of FIG. 15.
